SHOE CLEANING GUARD

Helen Cronin, Cincinnati, Ohio

Application August 13, 1946, Serial No. 690,225

3 Claims. (Cl. 36—72)

1

This invention pertains to an improved shoe polishing and cleaning shield and has, for one of its principal objects, the provision of means which can be readily attached to a shoe before polishing and cleaning the same whereby a better, quicker, and neater job is accomplished.

One of the important objects of this invention is the provision of a shoe cleaning guard which can be readily positioned in place between the upper and the sole and heel portion of a shoe whereby the soles and heels are shielded when the uppers are being cleaned and polished, and whereby the uppers are shielded when the soles and heels are being cleaned and polished.

Still another object is to provide a shoe cleaning guard which may be readily slipped over the upper of the shoe and positioned between the shoe upper and the sole and which may be turned downwardly over the soles for cleaning the uppers of the shoes and which may be moved upwardly to expose the sole for cleaning.

A further important object of the invention lies in the provision of a shoe polishing or cleaning shield which can be readily adjusted to fit substantially any size and shape of shoe which, after being so adjusted, will be securely held in desired position while the polishing or cleaning operation is being performed.

Further features and advantages of this invention will appear from a detailed description of the drawings in which:

Figure 1 is a side elevation of a shoe showing the shoe guard attached for cleaning and polishing the upper of the shoe.

Figure 2 is a fragmentary view of the toe portion of the shoe shown in Figure 1 with the shoe guard attached for cleaning and polishing the upper.

Figure 3 is another side view of the shoe shown with the shoe guard attached for exposing the sole to cleaning and polishing.

Figure 4 is a view end elevation of the toe portion of the shoe with the guard in position exposing the sole and covering the toe portion of the upper.

Figure 5 is a plan view of the elastic shoe guard shown in Figures 1, 2, 3, and 4 when removed from the shoe.

As illustrative of one embodiment of this invention, there is shown in Figure 1 a shoe having an upper U and a sole S to which the shoe guard, Figure 5, comprising an elastic band of material 15 is applied. This elastic band 15 has a centrally located hole 16 formed in the elastic material which is shaped substantially to that of

an average shoe sole. Preferably, the portions 17 and 18 are provided with stiffening portions where the shoe guard engages the sole and upper at the instep of the shoe so as to maintain proper contact of the shoe guard around the shoe.

In Figure 1, the shoe guard 15 is shown placed over the shoe sole and fitting into the notch 19 formed between the upper and sole of the shoe.

10 In this case, the shoe guard 15 is shown stretched down over the sole S so as to protect it and permit cleaning and polishing of the upper portion U of the shoe without in any way soiling the sole during this operation. After the upper has been 15 appropriately cleaned and polished, the shoe guard is then folded back over the upper U, as shown best in Figures 3 and 4, so as to expose the sole S for cleaning and polishing. In this position, the shoe guard 15 fully protects the upper 20 of the shoe so that the sole may be readily treated without in any way soiling the upper which has been previously cleaned. After the polishing operations have been thus completed on the upper and the sole, the guard is simply stretched off 25 of the shoe and the job is done in a neat and efficient manner.

There has thus been provided an improved shoe cleaning guard adapted to at one time protect the sole while cleaning and polishing the upper and which may be readily and quickly readjusted to allow the exposure of the sole for cleaning and polishing while protecting the upper of the shoe.

While the apparatus herein disclosed and described constitutes a preferred form of the invention, it is to be understood that the apparatus is capable of mechanical alteration without departing from the spirit of the invention and that such mechanical arrangements and commercial adaptations as fall within the scope of the appendant claims are intended to be included herein.

Having thus fully set forth and described this invention, what is claimed as new and desired to be secured by United States Letters Patent is:

1. A shoe cleaning guard comprising an elastic sheet of material formed with a central opening having approximately the shape of a complete shoe sole, said opening including communicating recesses, one of said recesses being adapted to receive the forward main portion of said sole while the other recess is adapted to receive the heel portion of said sole, whereby said sheet may be stretched over a shoe and positioned adjacent the connection of the upper with the sole to at

one time form a guard for the sole while cleaning the upper and to at another time form a guard for the upper while exposing the edge and top of the sole for cleaning.

2. A shoe cleaning guard comprising an elastic sheet of material, a central opening formed in said sheet for placement of said sheet over a shoe adjacent the juncture of the sole and upper thereof, rigidifying members adjacent said opening to stiffen said guard adjacent the instep portions of said shoe when said guard is placed over said shoe, said guard being adapted to be folded over said sole to guard the same while cleaning the upper of the shoe and to be folded back over the upper when cleaning the sole of said shoe.

3. A shoe cleaning guard comprising an elastic sheet of material, a reduced sized opening formed in said sheet when unstretched having substantially the shape of a shoe sole, stiffening members adjacent said opening for placement adjacent each side of said shoe, said elastic guard being adapted to be stretched over a shoe and positioned thereon adjacent the juncture of the sole and upper of said shoe so that it is adapted

4
to shield the sole while cleaning the upper and for shielding the upper while cleaning the sole of said shoe.

HELEN CRONIN.
